CLAIM

The ornamental design for a putter type golf club head, as shown and described.

DESCRIPTION

FIG. 1 is a rear perspective view of a putter type golf club head showing my new design.

FIG. 2 is a front elevational view thereof.

FIG. 3 is a bottom view thereof.

FIG. 4 is a top plan view thereof.

FIG. 5 is a rear elevational view thereof.

FIG. 6 is a toe end elevational view thereof.

FIG. 7 is a heel end elevational view thereof; and,

FIG. 8 is a rear perspective of a second embodiment of the putter type golf club head as disclosed in FIG. 1, the undisclosed sides are identical to that disclosed in the first embodiment.

The broken line showing is for illustrative purposes only and forms no part of the claimed design.
